Application August 6, 1932, Serial No. 627,699
In Germany May 21, 1932

11 Claims. (Cl. 178—6)

My invention relates to television scanning apparatus.

This application is a continuation in part of my former application Serial No. 602,972 filed 5 April 4, 1932, entitled "Television apparatus".

An object of the parent application is to describe scanning apparatus comprising a stationary member provided with peripherally disposed scanning elements for analyzing or recombining 10 an image, and a rotary reflector for projecting the image onto the analyzing member, or for receiving an image from the recombining member, as the case may be. With the apparatus there described, the rotary reflector is arranged 15 at an angle of about 45° to the axis of the driving motor, as a result of which the image is, for example on transmitting, not only rotated about the axis of the motor for variable projection on the stationary analyzing member, but also revolves once in its plane for each revolution of the motor.

For compensating this revolution of the image in its plane I have as set forth in the parent application, provided a correcting prism, arranged intermediate the reflector and the objective of the apparatus, and adapted to rotate at half the speed of the reflector. It has been found, however, that the addition of this correcting prism introduces practical difficulties in 25 operation. For rotating the prism a second motor must be provided which should revolve at exactly half the speed of the motor carrying the reflector, and it has been found rather difficult to secure and maintain this precise rotary 30 relation between the two motors. An additional objection to the correcting prism results from the increased length of optical paths traversed by the scanning beam within the apparatus thus introduced, so that either increased light-losses 35 must be accepted or the optical parts of the apparatus must be made very large.

The object of my present invention is to overcome these drawbacks by eliminating the correcting prism itself. To this end the stationary 45 member, which may be a drum, having spaced about it peripherally a plurality of scanning elements, such as having a helical row of apertures relatively positioned for analyzing or recombining an image, is combined with a coaxial rotary 50 reflector having a plane its reflecting surface substantially parallel to its axis of rotation. The image is projected onto this rotary reflector or vice versa, by a corner mirror fixed to the inside wall of the drum. The rotary mirror having its 55 reflecting surfaces parallel to its axis of rota-

tion does not cause any revolution of the image in its plane, so that the correcting prism is rendered superfluous and all the difficulties connected with the addition, arrangement and driving of this prism are avoided.

In the accompanying drawing apparatus embodying my invention is illustrated diagrammatically by way of example.

Fig. 1 is an elevation of my television receiving apparatus.

Fig. 2 is a sectional plane view of the same.

Fig. 3 is a horizontal section of a television transmitting apparatus in accordance with my invention.

Referring to Figs. 1 and 2, 1 is the stationary 70 drum-shaped analyzing or recombining member provided with a helical row of scanning elements or apertures 5. In the centre of this drum and coaxial therewith a rotary reflector 2 is provided which is driven by the motor 3, the entire 75 unit being of small mass in relation to the drum. This reflector is arranged so that its reflecting surfaces are substantially parallel to its axis of rotation as shown. Surrounding drum 1, 4 is a 80 photo-cell of helical shape so that it covers all the apertures 5.

The light rays falling through the apertures 5 on the reflector 2 are projected by it onto the corner mirror 6, affixed to the inside wall of the drum 1 in the space between two neighbouring 85 apertures 5, and are reflected to the objective 7 for projection onto a screen.

With the transmitter shown in Fig. 3 the arrangement is substantially the same except that the glow-lamp 4 is replaced by a photocell of 90 the same shape. It would also be possible to use the same corner mirror here but thereby large light-losses would be introduced owing to the small area of the mirror placed in the space between adjacent apertures of the drum, as here the mirror has to reflect the entire picture while in the receiver only single picture points are reflected one after the other. Therefore it is 95 advantageous to use a mirror of larger size in the transmitter. As such mirror would cover 100 some of the apertures of the drum it has to be provided with corresponding apertures 8 enabling the passage of the light-rays from the rotary mirror 2 to apertures 5.

By means of the apparatus according to my 105 invention it is also possible to control the definition of the picture during the transmission. To this end another corner mirror 9 is arranged diametrically oppositely to the corner mirror 6. Each time the rotary mirror 2 comes into hori- 110

zontal position the entire image is reflected from the corner mirror 6 onto the corner mirror 9 and therefrom to the opaque glass plate 10 whereby the condition of focus can be continually observed by the lens 11.

I claim:

1. Television apparatus comprising a stationary circular member having spaced about it peripherally a plurality of scanning elements 10 relatively positioned for scanning, and a coaxial rotary reflector arranged to provide for reflection therefrom occurring along lines located in planes substantially perpendicular to the rotary axis, an optical path progressively established between 15 contiguous areas of a scanned field and said spaced elements in succession.

2. Television apparatus comprising an electro-optical translating device, a stationary drum having spaced about it peripherally a plurality of 20 scanning elements relatively positioned for scanning, and a rotary reflecting member, arranged coaxially within the drum, and cooperating with said spaced elements progressively to establish, by reflection from said member occurring in a 25 plane substantially perpendicular to the rotary axis, an optical path between said translating device and successive elemental areas of a scanned field.

3. Television apparatus comprising an electro-optical translating device, an objective, a stationary drum having spaced about it peripherally a plurality of scanning elements relatively positioned for scanning, and a rotary reflecting member, arranged coaxially within the drum, and 35 cooperating with said spaced elements progressively to establish, by reflection from said member occurring in a plane substantially perpendicular to its rotary axis, an optical path between said translating device and successive elemental 40 areas of said objective.

4. Television apparatus comprising an electro-optical translating device, an objective, and means for progressively establishing an optical path between said translating device and successive elemental areas of the objective, comprising, a stationary drum having spaced about it peripherally a plurality of scanning elements relatively positioned for scanning, a rotary reflecting member, arranged coaxially within the 50 drum, and cooperating with said spaced elements to establish said optical path by reflection from said member occurring in a plane substantially perpendicular to its rotary axis, and a stationary reflector positioned to direct the optical path at 55 an angle between the rotary reflecting member and the objective.

5. Television apparatus comprising a stationary drum having a helical row of apertures for scanning, and a coaxial rotary reflector arranged 60 within the drum adapted progressively to establish, by reflection therefrom occurring in a plane substantially perpendicular to its rotary axis, an optical path between contiguous elemental areas of a scanned field and said apertures successively.

6. Television apparatus comprising an electro-optical translating device, a stationary drum having a helical row of apertures for scanning, and a rotary reflecting member arranged coaxially within the drum and cooperating with said apertures 70 progressively to establish, by reflection from

said member occurring in a plane substantially perpendicular to its rotary axis, an optical path between said translating device and successive elemental areas of a scanned field.

7. Television apparatus comprising a stationary drum having a helical row of apertures for scanning, an electrooptical translating device surrounding the drum in alignment with said apertures, a rotary reflecting member arranged coaxially within the drum and cooperating with 85 said apertures progressively to establish, by reflection from said member occurring in a plane substantially perpendicular to the rotary axis, an optical path between said translating device and successive elemental areas of a scanned field. 90

8. Television apparatus comprising an electro-optical translating device, an objective, a stationary drum having a helical row of apertures for scanning, and a rotary reflecting member arranged coaxially within the drum and cooperating 95 with said apertures progressively to establish, by reflection from said rotary member occurring in a plane substantially perpendicular with its axis, an optical path between said translating device and successive elemental areas of said objective. 100

9. Television apparatus comprising an electro-optical translating device, an objective, and means for progressively establishing an optical path between the said translating device and successive elemental areas of said objective, comprising, a stationary drum having a helical row of apertures, a rotary reflecting member arranged coaxially within the drum and cooperating with the apertures to establish said optical path by reflection from said member occurring in a plane 110 substantially perpendicular to the rotary axis, and a stationary reflector positioned to direct the optical path at an angle between the rotary reflecting member and said objective.

10. Television apparatus comprising an elec- 115 trooptical translating device, an objective, and means for progressively establishing an optical path between the translating device and successive elemental areas of said objective, comprising, a stationary drum having a helical row of 120 apertures, a rotary reflecting member arranged coaxially within the drum and cooperating with the apertures to establish said optical path by reflection from said member occurring in a plane substantially perpendicular to the rotary axis, 125 a mirror fixed to the inner wall of said drum for directing the optical path at an angle between the rotary reflecting member and said objective, a second mirror arranged within the drum opposite to the first for projecting an image from said 130 objective onto a second objective.

11. Television apparatus comprising a stationary substantially circular member having spaced about it peripherally a plurality of scanning elements relatively positioned for scanning, and a 135 reflector mounted to rotate about an axis substantially parallel to the axis of said member and having every element of its reflecting surface extending in the direction of the axis substantially linear and parallel to said axis, to provide by 140 reflection therefrom an optical path progressively established between contiguous areas of a scanned field and said spaced elements in succession.
